ROLLER MOUNTING DEVICE FOR A PAINT APPLICATOR

Vern T. Touchett, Whitefish Bay, Wis., assignor, by mesne assignments, to E Z Paint'r Corporation, Milwaukee, Wis., a corporation of Delaware

Application July 25, 1951, Serial No. 238,439

3 Claims. (Cl. 15—230)

This invention relates to a roller type paint applicator and particularly to an improved handle construction therefor.

One of the features of this invention is to provide a manipulating apparatus removably engageable with a hollow cylindrical paint-applying portion of a roller type paint applicator with this apparatus comprising a handle portion and a core member rotatable thereon and insertable within the cylinder portion, the core member including a pair of spaced collars and a segment of a cylinder extending therebetween with the segment including end portions enclosed by the collars to hold the core member assembled and an outwardly-extending spring edge portion located between but spaced from the collars. Another feature of the invention is the provision of such a structure wherein the core member includes a plurality of longitudinal segments of a cylinder arranged seriatim to describe substantially a cylinder with each end portion of a segment within a collar having an edge bearing against an edge of the next end portion, each segment having an outwardly-extending spring edge portion located between but spaced from the collars with each end of a spring edge portion being defined by a deep notch in the segment adjacent to a collar, each end portion of a segment within a collar being provided with a circumferential groove to give rigidity thereto and each segment being provided with a second circumferential groove extending from the bottom of a notch around the remainder of the segment substantially parallel to the first groove and each collar having an inturned inner edge engaging one of these second grooves. A further feature of the invention is the provision of a manipulating apparatus wherein the core member includes an outwardly-extending spring member having a sloped lateral edge portion acting as an inclined plane lever to aid in forcing the spring member inwardly when the edge of the cylindrical paint-applying member is forced over this edge. Yet another feature of the invention is the provision of such a structure wherein the core member includes a pair of spaced collars and a plurality of longitudinal segments of a cylinder extending therebetween, the ends of the segments being enclosed by the collars without substantial compression of the segments and each segment having an outwardly extending spring edge portion located between the collars. Other features and advantages of the invention will be apparent from the following description of one embodiment of the invention as shown in the accompanying drawings. Of the drawings:

Fig. 1 is a plan view of a manipulating handle embodying the invention with the roller being shown in broken lines.

Fig. 2 is an enlarged end elevation of the core member of the embodiment of Fig. 1 taken from the left hand end thereof.

Fig. 3 is a section taken substantially along line 3—3 of Fig. 2.

Fig. 4 is a section taken substantially along line 4—4 of Fig. 3.

2

Fig. 5 is a view similar to Fig. 4 but showing the spring portions in unstressed condition.

When paint is applied to a surface by means of a roller applicator the applicator is ordinarily constructed so that the absorbent surface of the roller may be at least partially saturated with paint and then rolled over the surface to be painted. The absorbent roller is ordinarily freely rotatable on a manipulating handle. As the paint absorbing roller eventually becomes worn and contaminated with dried paint it is necessary that the roller be replaced with a fresh one. In the applicator of this invention applicant has provided a structure wherein the cylindrical roller is firmly held in place on the manipulating handle by a spring action but may be readily removed for replacement by a new applicator. The core member of the manipulating handle apparatus is of sturdy but inexpensive construction and is preferably made by interlocking sheet metal portions having integral spring portions.

20 In the embodiments shown in the drawings the paint applicator comprises a manipulating apparatus including a handle portion 10 and a core member 11. The core member 11 is rotatable on a straight axle portion 10a of the handle. As shown in the drawings, the handle portion 10 comprises a metal rod of circular cross section bent to form the axle portion 10a with the end opposite the axle portion being fitted with a hand engageable member 12.

The core member 11 is arranged to removably retain a hollow cylindrical paint-applying member 13. This member includes a rigid cylindrical portion 13a having fibers 13b on the outer surface thereof. Such a paint-applying roller is well known in the art. When the applicator is used to spread paint on the surface, the outer part of the fibrous portion 13b is immersed in paint and the roller is then rolled over the surface to be painted.

30 The core member 11 that is removably retained within the hollow roller 13 comprises a pair of substantially cylindrical collars 14 rotatably mounted on the axle 10a and spaced apart a distance substantially corresponding to the length of the paint-applying member 13. Each of the collars 14 has a closed inwardly recessed end 14a attached to a substantially cylindrical bearing rotatable 40 on the axle 10a, the bearing at the outer end of the axle being designated as 15 and that at the inner end as 15a. The opposite open end of each collar 14 extends toward the other collar, as shown in Fig. 3.

Held by the collars 14 are a pair of substantially semi-cylindrical sheet metal segments 16 which together substantially describe a cylinder. Each of the segments 16 has an end located within a collar 14 with each end portion 16a being provided with a circumferential groove 16a to reinforce it against bending. Each of the end portions within a collar 14 is provided with an inwardly directed flange 16b bearing against a similar flange on the adjacent section. Thus, each semicylindrical section 16 has two substantially diametrically opposite flanges 16b each bearing against a similar flange on the next segment 16 with all these flanges being located within the collars 14.

50 In order to lock the semicylindrical segments 16 in place, each of the collars 14 is provided with an inturned inner edge 14b engaging a corresponding groove 16c in the sheet metal segments 16. Thus the assembly of collars 14 and segments 16 are rigidly held by the edge portions 14b of the collars bearing inwardly against the segments 16 and the flanges 16b of the segments bearing 55 against each other. The circumferential grooves 16a and 16c add rigidity to the structure.

60 Each segment 16 is provided with a spring portion 16d

extending generally outwardly when unconfined, as shown in Fig. 5. These spring portions are provided by cutting generally V-shaped notches 16e from one edge of a segment 16 with each notch being located adjacent an end portion 16f that is held within a collar 14. The bottom of the deep notch 16e is located at approximately the midpoint of a segment 16 and is positioned at the end of the inwardly directed groove 16c that is positioned in the uncut portion of the segment adjacent an end portion 16f to give rigidity to the structure. Thus, the groove 16a within the collar 14 and the groove 16c just outside the collar 14 aids in providing a rigid construction at each end of the core member.

The spring portion 16d, defined by the part of each segment 16 between the V-shaped notches 16e, is distorted outwardly as shown in Fig. 5 to extend beyond the cylinder defined by the undistorted portions of the segments 16. When the core member is inserted within the tubular portion 13a of the roller 13 these spring portions 16d bear against the inner surface of the tubular portion 13a and hold the roller 13 on the handle 10. When the paint-applying roller is removed from the handle it is necessary only to grasp the roller and force it to the left, as viewed in Figs. 1 and 3. When a new roller is applied, it is pressed on in the reverse direction. The sloped inner edge of each groove 16e aids in pressing the roller into place as this edge acts as an inclined plane to produce leverage on each spring portion 16d and force it inwardly when the leading edge of the roller is forced across the edge 16e.

In order to hold the core member properly located on the handle portion 10 the innermost bearing 15a bears against a backing member 17 fastened to the axle 10a. The opposite bearing member 15 is held in place by an outwardly located washer 18 held on the end of the axle 10a by a screw 19. When it is necessary to remove the core member 11 the screw 19 and washer 18 may be removed and the core member slipped off the end of the axle.

As can be seen from the drawings, the cylindrical portions of the collars 14 do not compress the segments 16. The parts are held in assembled relationship primarily by inwardly-extending inner flanges 14b on the collars engaging the grooves 16c. This lack of initial compression of the parts is of decided advantage in providing a superior applicator. These advantages include ease of assembly as the parts may be made with greater tolerances and there is no need to compress carefully and laboriously each cylindrical segment to fit it carefully within the collars. This avoidance of initial compression also results in longer life of the applicator as there is no necessity for repeatedly bending outwardly the resilient edges of the segments in order that the required pressure will be maintained at all times against the inner surface of the cylinder 13. As the new applicator avoids initial compression of the parts there is also less danger of the cylindrical segments assuming a permanent set which is liable to occur when the parts are constantly under compression. This is of particular importance where the parts are made of thin sheet metal members that are more susceptible to permanent set.

Having described my invention as related to the embodiment shown in the accompanying drawings it is my intention that the invention be not limited by the details of description unless otherwise specified but rather be construed broadly within its spirit and scope as set out in the accompanying claims.

I claim:

1. In a paint applicator having a hollow cylindrical paint-applying member, manipulating apparatus removably engageable therewith, comprising: a handle portion, and a core member rotatable thereon and insertable within the cylindrical member, the core member including a pair of spaced collars and a segment of a cylinder extending therebetween, the segment including end portions enclosed by the collars to hold the core member assembled, an outwardly-extending spring edge portion located between but having its ends spaced from the collars, each end of the spring edge portion being defined by a deep notch in the segment adjacent to a collar with the edge of the notch further from the collar having a relatively great slope away from the adjacent collar toward the free edge of the spring edge portion to act as an inclined plane lever and force the spring edge portion inwardly when the cylindrical paint-applying member is forced over this edge.
2. In a paint applicator having a hollow cylindrical paint-applying member, manipulating apparatus removably engageable therewith, comprising: a handle portion, and a core member rotatable thereon and insertable within the cylindrical member, the core member including a pair of spaced collars and a plurality of longitudinal segments of a cylinder arranged seriatim to describe substantially a cylinder, the segments including end portions enclosed by the collars to hold the core member assembled with each end portion within a collar having an edge bearing against an edge of the next end portion, each segment having an outwardly-extending spring edge portion located between but having its ends spaced from the collars with each end of a spring edge portion being defined by a deep notch in the segment adjacent to a collar, each end portion of a segment within a collar being provided with a circumferential groove to give rigidity thereto and each segment being provided with a second circumferential groove extending from the bottom of a notch around the remainder of the segment substantially parallel to the first groove, each collar having an inturned inner edge engaging one of said second grooves.
3. In a paint applicator having a hollow cylindrical paint-applying member, manipulating apparatus removably engageable therewith, comprising: a handle portion, and a core member rotatable thereon and insertable within the cylindrical member, the core member including a pair of spaced collars and a plurality of longitudinal segments of a cylinder extending therebetween, said segments having end portions abutting seriatim in cylindrical form, the ends of the segments being enclosed by the collars without substantial compression of said segments and each segment having an outwardly-extending spring edge portion located between but having its ends spaced from the collars.
